INDICATOR

Application filed May 12, 1926. Serial No. 108,474.

This invention relates to indicators, and more particularly to an indicator or gauge for use on locomotives, operable by the exhaust back pressure to indicate to the locomotive engineer at all times whether his reverse lever is at the proper point of cut-off for maximum efficiency of operation under the particular operating conditions then obtaining, and, further, if the reverse lever is not set 10 for the proper cut-off, will indicate directly in which direction the engineer should move the lever to obtain maximum efficiency. The device may, therefore, be termed a direct-reading indicator for adjusting cut-off.

It should be understood that the exhaust back-pressure in any locomotive at any time is determined by four conditions, namely: speed, boiler pressure, throttle opening, and cut-off, and that for any given locomotive 15 there is a particular back-pressure at which it will operate at maximum efficiency. If, then, the locomotive be operated constantly at that back-pressure, the maximum economy and capacity possible at any and every point 20 throughout its operating range will be obtained. Ordinarily the engineman hooks down the reverse lever at low speeds and on heavy pulls and hooks it up as speed increases, making the shifts in its position as his judgment dictates, and basing his judgment principally upon the sound of the exhaust. While 25 this is done, of course, to utilize the steam expansively as speed increases and to reduce back-pressure, it is only an approximation of the conditions of economy which would obtain were the locomotive to be operated with certainty at a predetermined constant back-pressure. Any change in speed, boiler pressure, or throttle opening, or two or all of them, 30 obviously will cause a change in the back-pressure, which, if the cut-off be suitably altered, may be compensated for, that is, the back-pressure may be maintained substantially constant by proper manipulation of the reverse lever from time to time.

The primary object of the present invention is, therefore, the provision of an improved gauge, actuated by the locomotive back-pressure, to give, at all times, a positive 35 indication to the engineman whether the re-

verse lever is in the position to maintain a certain predetermined exhaust back-pressure under the particular operating conditions existent at the moment, and, if it is not in that position, to indicate directly whether the reverse lever should be hooked up or hooked down, that is, whether the cut-off should be shortened or lengthened in order to restore the back-pressure to the predetermined point.

This invention is an improvement upon that disclosed in our co-pending application, Serial No. 63,827, filed October 21, 1925, and, in addition to the attainment of objects and advantages similar to those enumerated in said application, the present invention provides a mechanism of greater simplicity, fewer parts, more positive action, greater freedom from friction, decreased cost of manufacture, installation and maintenance, and easier and more accurate adjustment.

How all these advantages, and others which will doubtless occur to those skilled in the art, are attained, will appear from the following description of the preferred embodiment of the invention, reference being had to the accompanying drawings, wherein—

Fig. 1 is a front elevation of the apparatus; and

Fig. 2 is a sectional view of the same taken on the line 2—2 of Fig. 1.

In general, the device comprises a pressure chamber A having an enclosing cap or casing member 2, a chamber B thereabove having a casing member 3 within which are most of the moving parts of the apparatus, and the indicator proper C having a cap or casing 4 with a glass front 5. The casings 2 and 3 are secured together, as by the screws 6, and the casing 4 is secured to the casing 3 by suitable screws 7 passing through the dial 8 at each side thereof. The assembled device thus makes one compact unit, with a tight housing, capable of ready application to the back-head of the boiler, or of any other convenient mounting in the cab of the locomotive where its indication may be observed by the engineman.

The pressure chamber A, having a suitable pipe connection 9, contains within it an elongating or bellows diaphragm 10 mounted on

a peripheral ring 11 pinched between the cap 2 and the lower part of casing 3. Through the disc 12 of the diaphragm passes a spindle or bolt 13 extending up through a hole 14 in the bottom of casing 3 and carrying a spreader base or shouldered member 15 adapted to abut against and distribute the pressure on the disc 12. Above the member 15 is a spacer or collar 16 having a shoulder 17 adapted to limit the upward movement of the diaphragm by contact with the abutment or annular boss 18 on the bottom of casing 3. The downward movement of the diaphragm is limited by contact of the head 19 of the spindle 13 with a bolt or screw plug 20 screwed into the bottom of the cap 2 against an adjusting washer 48. On the upper end of the bolt 13 is screwed or otherwise mounted a cap piece 21 having a hardened point 22, the cap piece maintaining firmly in place the shoulder 15 and spacer 16, and the hardened point being adapted to bear within a concavity or depression on the under side of a rocking member or lever 23 in chamber B.

Within the operating chamber B is the lever 23 having one end fulcrumed on pin 24 and the other or free end engaging a push rod 25, the latter having a pointed end 26 adapted to rest in a cup or depression in the lever. Intermediate the ends of the lever are two concavities on opposite sides thereof, the lower adapted to receive the point 22 already referred to, and the upper adapted 35 to receive the pointed end 27 of a rod 28 which carries a fixed collar 29 against which a spring 30 is adapted to bear, the upper end of the spring seating on the bottom of a tension adjuster 31 which is screwed into the 40 top of the casing 3. The adjusting plug and its lock-nut 32 may have holes 33 and 34, respectively, for the insertion of any convenient tool for turning them. The spring 30 we have shown as being made of two lengths 30^a 45 and 30^b of commercially available size, with a seating collar or guide ring 30^c between them. By the use of a long spring we obtain a greater travel, and, consequently, greater movement of the lever 23 for any given 50 change in back pressure, which is desirable for the increased movement of the indicating hand thereby effected. The ring 30^c with its inner rib 30^d prevents undue lateral distortion of a spring of such length when under compression. The rod 25, working in guides 35, 36, mounted on the back of the dial 8, is connected, as by means of the cotter 37, to the end of a short lever or arm 38 mounted on 55 the rotatable shaft or pin 39.

The shaft 39 protrudes through the dial 8 and carries the indicating pointer or arm 40. A retaining nut 41 may be screwed on the outer end of the shaft, and a screw 42 is provided for the setting or adjustment of the

pointer on the shaft. A light tension spring 43, connected at one end to the lever 38, and at the other end to a fixed point, as, for example, to the guide 36, takes up any lost motion in the indicator parts, and exerts just sufficient pull to insure the pointer's movement toward the left when the lever 23 is moving downward during a decrease in back-pressure. The dial 8, as clearly shown in Fig. 1, has a mark 44 midway of the sides, with the legend "Hold" therebelow. To one side of the hold position is a suitable indication to "hook down" the reverse lever, and to the other side is an indication to "hook up".

For the moving parts of the apparatus, we have provided lubrication means consisting of oil cups 45, 46, and 47, adapted to lubricate respectively the indicator shaft 39, the sliding contact between rod 28 and tension adjuster 31, and the pivot pin 24.

The initial adjustment and the operation of the device are substantially as follows:

The plug 20, at the bottom of the pressure chamber, is unscrewed and the adjusting washer 48 removed, after which the plug is replaced and run full in, bearing against the head 19 of spindle 13. With the plug screwed all the way in, the diaphragm 10 is held at the center of its travel. By means of the adjusting screw 42, the indicating hand 40 is then set on its shaft 39 so that it points to the "Hold" mark 44 on the dial. The tension on the spring 30 is next adjusted, and, for purposes of illustration, let us assume that the locomotive to which the device is applied must be operated, for greatest efficiency, at a constant back-pressure of 10 pounds. Fluid pressure through a test gauge is admitted by pipe 9 to chamber A, and by means of the adjusting plug 31 and lock nut 32, the compression of spring 30 is adjusted, so that the pointer 40 will be opposite the mark "Hold" when the pressure, as shown on the test gauge, is 10 pounds. In other words, for any particular locomotive, the adjustment of the spring 30 must be such as to balance the pointer at mid-position against a pressure equal to that back-pressure at which it is desired to operate that particular locomotive.

During operation of the engine, pressure from the exhaust cavities of the cylinders, or from any suitable point in the exhaust line (not shown), is admitted through the connection 9 to the chamber A, tending to compress the diaphragm, which, in the absence of such pressure, has expanded under the force exerted by spring 30 until the head 19 is in contact with plug 20, the pointer 40 being at that time over the position "Hook down" at the left of the dial. As the throttle is opened, and/or as speed increases, the back-pressure increases and compresses the diaphragm against the force of spring 30, rocking the lever 23 upward, and actuating rod 25, lever 38 and shaft 130

39 to move the pointer 40 toward "Hold" position on the dial. After the point "Hold" has been reached, a further increase in throttle opening or speed, or an increase in boiler pressure, or further increase in any two or 5 more of them, will cause the pointer to move still farther to the right, over the region marked "Hook up". The engineer then hooks up, or hooks back, the reverse lever, thereby 10 shortening cut-off, reducing back-pressure, and restoring the pointer to "Hold" position. Thus, any variation, either by way of increase or decrease in boiler pressure, speed, or throttle opening, gives to the engineman a positive 15 direct indication whether and in which direction he should move the reverse lever to maintain the predetermined normal operating back-pressure, and the operation of the locomotive will be as follows:—

20	Indicator hand over region	Reason for indication	Action of engineman and result
25	Down	Drop in back-pressure below pressure at "Hold" due to decrease in speed, boiler pressure, or throttle opening, or combination of two or all of them.	Moves reverse lever down, lengthening cut-off and restoring back-pressure. Hand moves to "Hold" position.
30	Up	Rise in back pressure above pressure at "Hold", due to increase in speed, boiler pressure, or throttle opening, or combination of any two or all of them.	Moves reverse lever up, shortening cut-off and reducing back-pressure. Hand moves to "Hold" position.
Hold	Hold	No change in speed, boiler pressure, or throttle opening.	Does not move reverse lever.

35 It will be obvious that our device is capable of ready adjustment for any particular installation, since the spring tension adjusting plug 31 is accessible without the opening or removal of any part of the apparatus. The 40 lubrication means is equally accessible, and very simple and reliable in operation. The moving parts offer a minimum of friction, resulting, of course, in positive and accurate action, and the whole structure, while rugged 45 enough to withstand any shocks imposed by the exhaust steam pressure, provides, by means of the long spring and the elongating or bellows diaphragm in combination with the movement-multiplying levers, a sufficient 50 long travel of the indicating hand to register even a slight change in pressure, one pound difference in pressure, for instance, being sufficient to cause a movement of the pointer nearly half-way across the dial.

55 We claim:—

1. A direct-reading indicator for adjusting locomotive cut-off comprising, in combination, a movable member, a bellows-diaphragm actuated by locomotive exhaust pressure, 60 sure adapted to exert a force on one side of said member, tension means adapted to exert a force on the other side of said member to position it variably in proportion to variations in the exhaust pressure, and indicating 65 means actuated by said member.

2. A direct-reading indicator for adjusting locomotive cut-off comprising, in combination, a rocking member, a bellows diaphragm actuated by locomotive exhaust pressure adapted to exert a force on one side of said member, tension means adapted to exert a force on the other side of said member to position it variably in proportion to variations in the exhaust pressure, and indicating means actuated by said member. 70

3. A direct-reading indicator for adjusting locomotive cut-off comprising, in combination, a rocking member, means actuated by locomotive exhaust pressure adapted to exert a force on one side of said member, tension means adapted to exert a force on the other side of said member to position it variably in proportion to variations in the exhaust pressure, and indicating means actuated by said member, with an indicating dial associated therewith, together with means for adjusting the pressure of the tension means. 75

4. A direct-reading indicator for adjusting locomotive cut-off comprising, in combination, a flexible bellows diaphragm, means for admitting locomotive back-pressure thereto, tension means, a lever actuated in one direction by the bellows diaphragm and in another direction by the tension means and adapted to multiply the movement imparted to it, said lever being balanced by the tension means in various positions in accordance with variations in the back-pressure, and indicating means actuated by said lever. 80

5. A direct-reading indicator for adjusting locomotive cut-off comprising, in combination, a bellows diaphragm member, means for admitting locomotive back-pressure thereto, tension means, a lever actuated in one direction by said member and in another direction by the tension means and adapted to multiply the movement imparted to it, and indicating means actuated by said lever, including a movable indicating member and a stationary member in association therewith. 100

6. A direct-reading indicator for adjusting locomotive cut-off comprising, in combination, a bellows diaphragm member, means for admitting locomotive back-pressure thereto, tension means, a lever actuated in one direction by said member and in another direction by the tension means and adapted to multiply the movement imparted to it, and indicating means actuated by said lever, including a movable indicating member and a stationary member in association therewith bearing indications for adjusting the locomotive cut-off regardless of what the actuating back-pressure may be in pounds. 110

7. In combination, in an indicator, a movable pressure-actuated member, an indicating hand, operative connections therebetween, a tension device acting on said member in a direction against said pressure, stop means to limit the movement of said member 120

130

in each direction, and means for adjusting the relative positions of said member and said indicating hand comprising means adapted to hold the member at the center of its travel against the pressure of the tension device, and means for shifting the position of the hand with relation to the said operative connections.

8. In a back-pressure-operated indicator for adjusting locomotive cut-off, the combination of movable mechanism acted upon and variable in position over its range of travel by changes in locomotive back-pressure, indicating mechanism actuated by said movable mechanism, a fixed element associated with said indicating mechanism to give a normal cut-off indication when said mechanism is at a point intermediate its limits of movement and having means on each side thereof indicating variations from said normal point, and means of adjusting said indicating mechanism relative to said movable mechanism and said fixed element so that it may be set at said intermediate normal point when said movable mechanism is positioned at any given point of its travel under the influence of said back-pressure.

9. In a back-pressure-operated indicator for adjusting locomotive cut-off, the combination of movable mechanism acted upon and variable in position over its range of travel by changes in locomotive back-pressure, indicating mechanism actuated by said movable mechanism, a fixed element associated with said indicating mechanism to give a normal cut-off indication when said mechanism is at a point intermediate its limits of movement and having means on each side thereof indicating variations from said normal point, and means of adjusting said indicating mechanism relative to said movable mechanism and said fixed element so that it may be set at said intermediate normal point when said movable mechanism is positioned at any given point of its travel under the influence of said back-pressure, said movable mechanism including an elongated bellows diaphragm and a co-operating spring of a correspondingly long range of movement and of a relatively small difference of resistive power for a given movement.

10. In a back-pressure-operated indicator, the combination of mechanism actuated in one direction by locomotive back-pressure, yieldingly resistive means adjustable for pressure and acting on said mechanism in a direction opposite to the force exerted by said back-pressure, indicating mechanism actuated by said first-mentioned mechanism and adjustable relative thereto so that it may be set for a predetermined indication when said mechanism has been moved to the center of its travel by the back-pressure and under any given adjustment of the yieldingly resistive means.

11. In a back-pressure-operated indicator, the combination of mechanism actuated in one direction by locomotive back-pressure, yieldingly resistive means adjustable for pressure and acting on said mechanism in a direction opposite to the force exerted by said back-pressure, indicating mechanism actuated by said first-mentioned mechanism and adjustable relative thereto so that it may be set for a predetermined indication when said mechanism has been moved to the center of its travel by the back-pressure and under any given adjustment of the yieldingly resistive means, together with a housing and means for making the adjustment of the mechanism from the outside of the housing.

12. In mechanism of the character described, the combination of a housing, a lever pivotally mounted therein, means actuated by back-pressure and adapted to bear against said lever, tension means adapted to bear against the lever in an opposite direction, indicating mechanism actuated by said lever with a dial co-operating therewith, and a pressure-adjusting device for the tension means operable from without the said housing.

13. An indicator of the character described comprising, in combination, a casing, a flexible diaphragm therein, forming, with a portion of said casing, a pressure chamber, means for admitting fluid pressure to said chamber, a tension device in said casing, a pivoted member in the casing positioned by and between the diaphragm and the tension device, indicating mechanism operable by said pivoted member, an adjustable stop operable from outside the casing to position said diaphragm during adjustment of the indicating mechanism, and an adjusting means for the tension device operable from outside the casing.

14. In mechanism of the character described, a flexible member adapted to be actuated in one direction by fluid pressure, adjustable tension means adapted to actuate it in another direction, and adjustable stop means whereby its range of travel may be set independently of the adjustment of the tension means.

In testimony whereof we have hereunto signed our names.
